[57] **CLAIM**

The ornamental design for box for photo negative cases, as shown and described.

DESCRIPTION

FIG. 1 is a front elevational view of my new box for photo negative cases;

FIG. 2 is a left side elevational view thereof;

FIG. 3 is a right side elevational view thereof;

FIG. 4 is a top plan view thereof;

FIG. 5 is a bottom plan view thereof;

FIG. 6 is a cross-sectional view taken along line 6—6 of FIG. 1;

FIG. 7 is a cross-sectional view taken along line 7—7 of FIG. 2;

FIG. 8 is a perspective view thereof; and,

FIG. 9 is a perspective view thereof, with a photo negative case removed from the box for clarity of illustration. The broken line showing of the photo negatives and the human hand is for illustrative purposes only and forms no part of the claimed design.
